UNITED STATES PATENT OFFICE.

FREDERICK V. FLETCHER, OF BROOKLYN, NEW YORK.

GUARD FOR CLOSING THE HINGE-CREVICES OF DOORS.

SPECIFICATION forming part of Letters Patent No. 274,303, dated March 20, 1883.

Application filed December 28, 1882. (No model.)

To all whom it may concern:

Be it known that I, FREDERICK V. FLETCHER, of the city of Brooklyn, in the county of Kings and State of New York, have invented 5 a new and useful improvement in guards or screens for closing spaces between, above, and below the hinges of doors, of which the following is a specification.

My invention consists in a guard or screen 10 of novel form, which can be applied to new or old doors, between and above and below the hinges, to close the opening which is between the door and its jamb to which it is hinged; when the door is ajar or swung open; and which 15 prevents drafts of air and precludes the possibility of any one peeping through said opening.

The construction of the guard or screen and the manner of applying it are shown in the accompanying drawings, in which—

20 Figure 1 represents an elevation of a door and its frame with my improved guard or screen applied to them. Fig. 2 represents a horizontal section of one edge portion of the door and the jamb to which it is hinged, the 25 door being open. Fig. 3 represents a corresponding section with a guard or screen of modified form, the door being represented as closed; and Fig. 4 represents a sectional view of the two parts of the guard or screen shown 30 in Fig. 3.

Similar letters of reference designate corresponding parts in all the figures.

A designates the door, and B the jamb, to which it is attached by hinges C. Obviously, 35 when the door is ajar or swung open, a space of considerable width is formed between the door and jamb, above, below, and between the hinges C, and my guard or screen is employed to close this space.

40 The guard or screen is composed of two parts or members, D D', which may be made of metal, wood, or other material. The two parts are made in sections adapted to fit between and above and below the hinges C.

45 When the guard or screen is to be applied to

new doors I may secure the parts to the edge of the door and the corresponding face of the jamb in the same way that the leaves of the hinges are secured, and as shown in Fig. 2; but when the guard or screen is to be applied 50 to doors which are already hung I may make the parts D D' of the form shown in Figs. 3 and 4, and secure them by nails or screws to the faces of the door and the jamb, as shown in Fig. 3. I may advantageously make one of 55 the parts of the guard or screen with a rounded edge, a, like the edge of the part D', and the other part, D, may in such case have its edge b concave to fit snugly the rounded edge a. The rounded edge of the part D' should be 60 concentric with the pintles of the hinges C. The guard or screen, when constructed according to my invention, is sightly and does not mar the appearance of the door, and will prevent 65 drafts when the door is open and render it impossible for any person to look through the opening between the door and the jamb to which it is hinged.

What I claim as my invention, and desire to 70 secure by Letters Patent, is—

1. The guard or screen consisting of two members adapted to be secured one to the hinged edge of the door and the other to the adjacent jamb, substantially as herein described, and for the purpose set forth. 75

2. The guard or screen consisting of two members adapted to be secured to the hinged edge of a door and the adjacent jamb, and one of which has a rounded edge, a, substantially as and for the purpose herein described. 80

3. The combination, with a door-jamb and a door hinged thereto, of the guard or screen composed of two members attached to said jamb and door, substantially as and for the purpose herein described.

FREDERICK V. FLETCHER.
